UNITED STATES PATENT OFFICE.

FRITZ LUBBERGER, OF CHICAGO, ILLINOIS, ASSIGNOR TO AUTOMATIC ELECTRIC COMPANY, OF CHICAGO, ILLINOIS, A CORPORATION OF ILLINOIS.

SEMI-AUTOMATIC TELEPHONE-EXCHANGE SYSTEM.

1,306,824.

Specification of Letters Patent. Patented June 17, 1919.

Application filed June 16, 1910, Serial No. 567,298. Renewed April 12, 1919. Serial No. 289,745.

To all whom it may concern:

Be it known that I, FRITZ LUBBERGER, a subject of the Emperor of Germany, and resident of Chicago, Cook county, Illinois, 5 have invented a certain new and useful Improvement in Semi-Automatic Telephone-Exchange Systems, of which the following is a specification.

My invention relates to automatic or semi-10 automatic telephone exchange systems. It relates more particularly to semi-automatic systems in which the calls are answered by an operator, and in which the latter is provided with means for controlling one or 15 more automatic switches to extend or complete the calls. Ordinarily this is accomplished by a cord circuit which is included in the calling connection.

An object of my invention is, therefore, to 20 provide an arrangement whereby an operator at one exchange may, through the medium of a trunking connection, control the establishment of connection between calling and called lines of another exchange, which 25 calling connections exclude the trunking connection, the talking circuits being confined entirely to the exchange at which the calling and called lines terminate, whereby the operator may release the said trunking connection after connecting two lines together at 30 the other exchange, and then use the same trunking connection for answering other calls, thus making it possible to dispense with operators at the exchange where the 35 calling and called lines are located.

It will be seen that an arrangement of this kind is of considerable advantage in a system in which there is a branch exchange at which manual lines terminate, and which is 40 not large enough to warrant the employment of an operator to answer the calls. In such case, and by the provision of my invention, the calls at the branch exchange are answered by an operator at the main exchange, 45 and the calling and called lines at the branch exchange are connected together without the necessity of having the calling connection extend through the main exchange, the trunking connection to the operator's board 50 at the main exchange being excluded from such calling connections, and being used only for answering the calls and then controlling the automatic switches at the branch exchange to find the called lines, or to extend the calls. 55

Another object is to provide an improved connector for use in a system of this kind adapted especially for use when one party-line subscriber calls another on the same line, the said connector being provided with 60 improved means for enabling it to seize the calling party line, which is also, in the case of a reverting call, the called line as well, as will hereinafter more fully appear.

To the foregoing and other useful ends 65 my invention consists in matters hereinafter set forth and claimed.

In the accompanying drawings Figure 1 shows diagrammatically a subscriber's substation A with its line switch C, a master 70 switch D for controlling the group of line switches of which the switch C is a member, and two connector switches E and F, in a system embodying the principles of my invention. At L is shown a ringer generator, 75 and at I and I' are represented two busy signaling machines. There may, however, be but one such busy machine.

In Fig. 2 is shown a subscriber's substation A', a line switch H and an operator's 80 cord circuit O of said system.

Fig. 3 shows more in detail the mechanism and circuits of the master switch D.

Fig. 4 is a simplified diagrammatic representation of a complete system embodying 85 the principles of my invention.

Figs. 5, 6 and 7 are circuits of apparatus employed in the system and will be more fully described hereinafter.

The subscriber's substation shown at A 90 in Fig. 1 may be any suitable common battery manual substation to which has been added the push button 2 and resistance coil 3. The substation A comprises the usual receiver 4, switch hook 5, transmitter 6, ringer 95 7 and condenser 8. When the receiver is removed from the switch hook the hook 5 engages the contact point 9, thereby bridging the transmitter 6 and receiver 4 in series across the line conductors 10 and 11. When 100 the push button 2 is depressed it separates the springs 12 and 13, whereby the resistance 3 is included in the bridge across the line conductors 10 and 11.

The line switch C comprises an electro-magnet 23 and a plunger (not shown) attached to the plunger arm 14 and adapted to be thrust into a bank of contacts comprising the springs 15, 16, 17, 18, 19, 20, 21 and 22. The electromagnet 23 comprises four wind- 110

ings, viz.: a pull-in winding 24, a bridge-cut-off winding 25, a line winding 28 and a holding winding 27. The magnetic circuit of the windings 28 and 27 is separate from that of the windings 24 and 25. The general operation of the line switch C is as follows: When the receiver at the calling substation is removed from the switch hook, thereby bridging the talking circuit across the line 5 conductors, an energizing circuit is established through the line winding 28. The winding 28 attracts the armature 99, which presses the springs 29 and 30 into contact, whereby an energizing circuit is closed 10 through the windings 24 and 27. The winding 24, upon energizing, attracts the plunger arm 14 and the cut-off armature 31. The plunger arm 14 thrusts the plunger into the bank of an idle trunk and the cut-off 15 armature cuts the line winding off from the line conductors. When the plunger enters the bank a circuit is closed through the cut-off winding 25, which holds the plunger arm 14 and the armature 31 in their attracted 20 positions until the switch is released.

The master switch D (shown more in detail in Fig. 3) is a somewhat modified form of the general type disclosed in the *Western Electrician* of Chicago, Illinois, of January 30, 1908, and in the *American Telephone Journal* of New York, N. Y., of June 6, 1908. The said master switch D comprises the motor magnet 32 adapted to operate the ratchet wheel 33, which in turn operates the plunger shaft 34 through the medium of the arm 35 and connecting shaft 36. The master switch bank M is composed of the individual segments *a* and the common segment *b*. The wiper 37 is adapted to keep some 35 one of the individual segments *a* in electrical connection with the common segment *b*. The motor magnet relay 38 closes an energizing circuit through the motor magnet 32. The motor magnet relay is in turn energized 40 by the busy trunk relay 39. At the top of the connecting shaft 36 is a spacing cam or segment 40 having on its arc ten circular openings adapted to fit the pin 41 at the extremity of the armature 42^a of the motor magnet relay 38. This spacing cam 40 is fastened to the shaft 36 and rotates with it. When a trunk upon which is resting the wiper 37 is seized the busy trunk relay 39 is energized. The relay 39, upon energizing, 45 closes an energizing circuit for the motor magnet relay 38. The relay 38 then attracts its armature 42^a, which withdraws the finger 41 from the particular opening in the cam 40 in which it happens at the time to 50 be resting. Also, at the same time an energizing circuit is closed through the motor magnet 32. The motor magnet 32, being provided with interrupter springs, operates in a manner similar to that in which a buzzer 55 operates as long as its energizing circuit re-

mains closed. As soon as the motor magnet begins to operate the opening in which the pin 41 was resting is moved out of register with said pin and the motor magnet cannot then stop operating until the pin 41 engages the next opening in the spacing cam 40, when the shaft becomes locked and cannot be moved again until the relay 38 is energized.

The connector switch E is of the general type disclosed in United States Letters Patent No. 815,176, granted March 13, 1906, to Keith, Erickson and Erickson, and, as shown, is modified to operate in connection with a two-wire common battery system. Among other details it embodies the following features: The switch shaft (not shown) carries the wipers 43, 44, 45 and 45^a. The side switch is well known and comprises the switch wipers 46, 47, 48, 48^a and 49 which are under the control of the private magnet 50. The operation of the connector is controlled by the operator at the main exchange through the medium of the relays 51 and 52. When the side switch is in first position the relay 51 controls the vertical magnet 53, the purpose of which is to give the shaft and shaft wipers 43, 44, 45^a and 45 a vertical motion. The rotary magnet 54 imparts a rotary motion to the shaft and shaft wipers and is controlled by the relay 51 when the side switch passes to the second position. The private magnet is under the direct control of the private magnet relay 55. The means whereby the connector may be restored to normal position is provided by the release magnet 56, which is connected with the battery lead through the normal springs 57 and 58 when the shaft is raised one or more steps. The operation of the release magnet 56 is under the direct control of the slow acting release relay 59. The ringer relay 60 operates to connect the ringer generator L with the line of the called subscriber. When the ringer relay 60 operates, one side of the ringing circuit is grounded through the condenser 61. The condensers 62 and 63 divide the talking circuit through the connector E into two parts.

The connector F is of the same general type as the connector E, but is more in the nature of a local battery switch in that it does not furnish talking battery current to either substation. When the switch F is used in a connection the two substations receive their talking battery current from the main exchange. The connector F comprises the usual shaft wipers 64, 65 and 66, vertical magnet 67, rotary magnet 68, private magnet 69 and release magnet 70. This connector is operated by the operator at the main exchange by ground impulses over one side of the line through the relay 71. The switch F is provided with the usual slow acting release relay 72 and private magnet re-

lay 73. Each point of the private bank of the connectors F and E comprises two separate contacts insulated from each other and each connected to separate springs of the 5 bridge-cut-off relays of the line switches. The line switch H is of the same type as the line switch C (Fig. 1). The plunger of the line switch H is self alining—that is, whenever the plunger of the switch H is with- 10 drawn from the bank it immediately assumes a position opposite the same trunk before which the plungers that are in locked engagement with the plunger shaft are held. The plunger of the switch H is controlled 15 by the same master switch D that controls the plungers of the line switches C, but the line switch H has an auxiliary master switch bank M' which is similar to the master switch bank M (Fig. 1). The line switch H 20 is allotted to a trunk which ends at the main exchange in a key K'. From the bank terminals of the line switch H trunks lead to the connector switches E.

The operator's cord circuit O may be of 25 any suitable or approved type of manual common battery operator's cord circuit. As here shown, the cord O comprises the usual supervisory relays 76, 77, 78 and 79, lamps 80 and 81, keys K², K³ and K⁴ and condensers 82 and 83. The operator's telephone set Q, in addition to the usual transmitter 84, receiver 85 and induction coil 86, is equipped with a calling device 87 for operating the automatic switches at the branch exchange. The substation A' is an ordinary manual substation comprising a receiver 88, transmitter 89, condenser 90, ringer 91 and switch hook 92.

In order to give a clearer understanding of 40 my invention I will first describe how the operator at the main exchange may operate the branch exchange switches to effect a connection between the branch exchange substation A and a substation of the main exchange, or of another branch exchange. It will be assumed that the subscriber at substation A on line #44 desires to communicate with the main exchange substation A'.

When the subscriber at substation A re- 45 moves his receiver from the switch hook preparatory to making a call an energizing circuit is closed through the line winding 28 of the line switch C. The energizing circuit of the winding 28 extends from ground G' through springs 29 and 93 to line conductor 11, thence through the switch hook 5, contact point 9, receiver 4, push button springs 12 and 13 and transmitter 6 of substation A to line conductor 10, thence through 50 springs 95 and 94, line winding 28, spring 115, armature 42^a to the battery lead, thence through battery B to ground G. The line winding 28, upon energizing, attracts the armature 99, which presses the spring 30 55 into engagement with spring 29, thereby clos-

ing an energizing circuit through the pull-in winding 24. This circuit extends from ground G' through springs 29 and 30, windings 24 and 27 of the magnet 23 to the battery lead 98, thence through the battery B 70 to ground G. The winding 24, upon energizing, attracts the cut-off armature 31 and the plunger arm 14. The cut-off armature, in its energized position, separates the springs 93 and 95 from the springs 29 and 94, respectively, thus opening the circuit through the line winding 28. The armature 99, however, does not fall back immediately upon the opening of the circuit through the winding 28 because the winding 27 is included in the 80 circuit of the pull-in winding 24 and holds the armature 99 in an operated position, thereby maintaining the circuit through the pull-in winding 24. The armature 31 also separates springs 96 and 97, thereby disconnecting the bank springs 19 and 21 from each other. When the plunger arm 14 is attracted it forces the plunger in the bank, pressing the bank springs 15, 16, 17, 18, 19, 20, 21 and 22 into engagement in pairs. The 90 plunger arm, in its attracted position, also closes a contact between springs 100 and 101. The engagement of the bank springs 15 and 17 with the springs 16 and 18, respectively, furnishes an energizing circuit for the relays 95 102 and 103. This circuit extends from ground G² through relay 102, bank springs 18 and 17 to line conductor 11, thence through the substation A and back over line conductor 10, bank springs 15 and 16 to and 100 through relay 103 to the battery lead 98, thence through battery B to ground G. The relay 102, upon energizing, separates the springs 104 and 105 to maintain the circuit of the ringer relay open. The closure of 105 springs 106 and 107 of the relay 103 furnishes an energizing circuit for the cut-off winding 25 of the line switch C. This circuit extends from ground G³ through springs 106, 107, 22 and 21 and winding 25 to the 110 battery lead 98, thence through the battery B to ground G. The winding 25 thereupon energizes to hold the cut-off armature 31 and plunger arm 14 in their attracted positions after the winding 24 115 is deenergized. The closure of contact between springs 100 and 101 short-circuits the winding 27 of the magnet 23. This short-circuiting of the winding 27 allows the armature 99 to fall back, thus opening the 120 circuit of the pull-in winding 24 at a point between the springs 29 and 30. The engagement of bank springs 19 and 20 has no effect at this time. The closure of springs 106 and 107 of the relay 103, formerly mentioned, 125 also closes an energizing circuit for the busy trunk relay 39 of the master switch D and the relay 108 (Fig. 2), and also supplies a guarding potential to the contact 109 of the auxiliary master switch bank M' and to the 130

contact 110 of the bank M. The energizing circuit of the busy trunk relay 39 extends from ground G³ through springs 106 and 107, master switch bank contact 110, wiper 37 (which at this time is resting on the contact 110), common segment b and relay 39 to battery lead 98, thence through battery B to ground G. The relay 39, upon energizing, closes a circuit extending from ground G⁴ through springs 111 and 112 and motor magnet relay 38 to the battery lead 98, thence through the battery B to ground G. The relay 38 energizes upon the completion of this circuit, withdraws the pin 41 (Fig. 3) from the hole in the spacing cam 40 in which it is resting and closes an energizing circuit for the motor magnet 32. This circuit extends from ground G⁵ through the motor magnet 32, interrupter springs 113 and relay springs 114 and 42^a to the battery lead 98, thence through the battery B to ground G. The motor magnet 32, being provided with the interrupter springs 113, begins to operate, in a manner similar to that in which a 25 buzzer operates, to rotate the ratchet wheel 33 and consequently the plunger shaft 34 and all idle plungers that are in locked engagement with it. The motor magnet will continue to operate until the next opening in the spacing cam has been carried beneath the pin 41, by which time the wiper 37 will have been carried off the grounded contact 110, allowing the relays 39 and 38 to deenergize. Thus the pin 41 will drop into the next opening 30 of the spacing cam 40 and open the circuit of the motor magnet relay. If the next trunk after the one seized by the switch C is busy, however, the wiper 37 finds the corresponding segment a grounded, the relays 39 and 38 cannot deenergize and the master switch will continue to operate until the wiper finds a non-grounded contact, so that the plungers of the idle line switches C will come to rest opposite the bank terminals of 35 an idle trunk. As long as the pin 41 is not resting in one of the openings of the spacing cam the contact point 115 is out of engagement with the spring 42^a, thus cutting off battery from the line windings of the line 40 switches C, so that no switch C can be operated while its plunger is in motion.

The circuit which the relay 103 (Fig. 1) closes through the relay 108 (Fig. 2) extends from ground G³ through springs 106 and 107, 45 springs 117 and 116, conductor 118 and relay 108 to the battery lead 98, thence through the battery B to ground G. The relay 108, upon energizing, closes a circuit extending from ground G⁵ through springs 120 and 121, 122 and 123 to trunk conductor 124, thence through springs 126 and 127 of the key K' and through the relay 130 and battery B² to ground G. The relay 130, upon energizing, closes a circuit from ground G⁶ through the 50 signal lamp 131^a and battery B² to ground G to signal the operator. Upon receiving the signal the operator throws the key K' to separate springs 126 and 127 and close contact between springs 126 and 131, 128 and 132, whereby the operator's set Q is bridged across the trunk conductors 125 and 124. The plunger of the line switch H was moved away from the terminals of the trunk conductors 133 and 134 when the line switch C seized the switch E, so that the plunger of the 55 switch H must be brought back to its former position before it is tripped in. When the operator's set is bridged across the trunk conductors an energizing circuit is established for the line winding 135 of the line switch H. This circuit extends from ground G⁵⁰ through springs 120 and 121, springs 122 and 123, trunk conductor 124, springs 126 and 131 of key K', through the calling device 87, secondary winding of the induction coil 86 and receiver 85 of the operator's set Q, through springs 132 and 128 of key K', conductor 125, springs 136 and 137 and winding 135 to the battery lead 98, thence through the battery B to ground G. The 60 winding 135, upon energizing, attracts the armature 138 to bring the spring 139^a into engagement with the spring 122, thereby closing an energizing circuit for the master switch relay 38. This circuit extends from ground G⁵⁰ through springs 120, 121, 122, 139^a, 139 and 140, conductor 142 and relay 38 to battery lead 98, thence through battery B to ground G. The relay 38, upon energizing, closes the circuit through the 65 motor magnet 32 as before, and the master switch D begins to operate. The master switch D will continue to rotate until the wiper 143 of the auxiliary master switch bank M' strikes the contact 109 which, as has been explained, is supplied with a guarding potential from the connector. When the wiper 143 strikes the contact 109 the relay 144 is energized to open the circuit of the master switch relay 38 and energize the pull-in winding 145 of the line switch H. The 70 energizing circuit of the relay 144 extends from ground G³ (Fig. 1) through the springs 106 and 107, 116 and 117, conductor 118, contact 109, wiper 143, common segment 146 and relay 144 to the battery lead 98, thence through the battery B to ground G. The relay 144, upon energizing, shifts the spring 139 out of engagement with spring 140 and into engagement with spring 141. The engagement of the springs 139 and 141 provides an energizing circuit for the pull-in winding 145 extending from ground G⁵⁰ through springs 120 and 121, 122 and 139^a, 139 and 141, windings 145 and 147 to the 75 battery lead 98, thence through the battery B to ground G. The disengagement of springs 139 and 140 opens the circuit of the motor magnet relay 38, but the said relay 38 does not deenergize because the wiper 37 is 80

at that time passing over the contact 110, which is supplied with a guarding potential, as explained in connection with the operation of the line switch C. The energization 5 of the winding 145 of the line switch H occurs just as its plunger is passing in front of the bank containing the terminals of the trunk conductors 133 and 134. The plunger is thrust into this bank, forcing the springs 10 148 and 150 into engagement with the springs 149 and 151, respectively, and thereby extending the trunk conductors 125 and 124 through to the conductors 133 and 134. The plunger also closes the contact between 15 springs 152 and 153, thereby short-circuiting the winding 147, which allows the armature 138 to fall back and open the circuit of the pull-in winding 145. It is understood, of course, that the cut-off armature 154 pulls up 20 as soon as the winding 145 is energized, and opens the circuit of the line winding 135 in the same manner as explained for the switch C. As soon as the trunk conductors 124 and 125 are connected with the conductors 134 and 25 133 an energizing circuit is closed through the slow acting relay 156 of the line switch H and the relays 51 and 52 of the connector E. The relay 156, upon energizing, supplies an energizing circuit from ground G⁷ 30 through springs 158 and 159, through the cut-off winding 157 to the battery lead 98, thence through the battery B to ground G. The winding 157 serves to hold the plunger in the bank after the pull-in winding 145 35 has deenergized. The relays 51 and 52 are functionless at this time and their action will be explained later in connection with the connector E. The energizing circuit of the relays 156, 51 and 52 extends from ground G⁸ 40 through relay 52, conductor 133, springs 149 and 148, trunk conductor 125, through the operator's telephone set to trunk conductor 124 and through relay 156, springs 150 and 151, conductor 134 and relay 51 to the 45 battery lead 98, thence through battery B to ground G.

The operator's telephone set is now connected with the substation A through the condensers 62 and 63, and the operator may 50 ascertain the number of the substation desired. On learning that the substation A' of the main exchange is wanted the operator asks the calling subscriber to give his number and then to hang up the receiver and she 55 then restores the key K' to normal position. When the key K' is restored the operator's telephone set is disconnected from the trunk conductors and the circuit of the relay 156 is broken. The relay 156 then deenergizes 60 to open the circuit of the cut-off winding 157 of the line switch H. When the winding 157 deenergizes the plunger of the line switch H restores to normal position and leaves the operator's trunk 124—125 free for another 65 call. The plunger of the line switch H, be-

ing self-aligning, immediately resumes a position in locked engagement with the plunger shaft. When the subscriber at substation A hangs up the receiver the energizing circuit of the relays 103 and 102 is opened at 70 a point between the switch hook 5 and the contact point 9. The relay 103, upon deenergizing, permits the springs 106 and 107 to separate, thus opening the holding circuit of the winding 25 of the line switch C and removes the guarding potential from the master switch bank contact 110. The line switch C restores to normal position, leaving the connector switch E free for a local connection. The operator now inserts the plug p² 75 into the jack J² and signals the called substation A' by throwing the key K⁴ to bring the springs 160 and 161 into engagement with the springs 162 and 163, respectively. This cuts off the line and bridges the ringer generator across the line of the substation A'. After ringing the substation A' the key K⁴ is restored to normal position. When the subscriber at substation A' removes his receiver from the hook that substation is 80 supplied with talking battery current over a circuit extending from ground G⁹ through the relay 77, springs 164 and 160 of key K⁴, tip of plug p² and jack J², line conductor 119, through the transmitter 89, receiver 88 85 and switch hook 92 of substation A', line conductor 129, through the sleeve of the jack J² and plug p², springs 161 and 165 of key K⁴ and relay 79 to battery B', thence to ground G. Since the relays 77 and 79 both 90 carry current the armature 166^a remains in normal position, thus maintaining the circuit of the supervisory lamp 80 open. The operator now inserts the plug P' into the jack J', throws the key K² to bring the 105 springs 166 and 167 into contact with the springs 168 and 169, respectively, and calls the subscriber A by means of the connector F. When the plug P' is inserted into the jack J' and the key K² is thrown, as described, an energizing circuit is completed from ground G¹⁰ through springs 169 and 167, receiver 85, secondary winding of the induction coil 86, calling device 87, springs 168 and 166, tip conductors of plug P' and 110 jack J', trunk conductor 170, side switch wiper 172 and relay 71 to the battery lead 98, thence through the battery B to ground G. The relay 71, upon energizing, shifts spring 173 out of engagement with spring 120 174 and into engagement with spring 175, whereby an energizing circuit is closed through the slow acting release relay 72. This circuit extends from ground G¹¹ 125 through springs 173 and 175 and through relay 72 to the battery lead 98, thence through battery B to ground G. The shifting of spring 176 of the relay 72 disconnects the release magnet 70 from the spring 174 of the relay 71 and connects said spring 174 130

with the vertical magnet 67 preparatory for impulses. When the operator operates the calling device 87 for the first digit 4 the circuit of the relay 71 is opened four times. 5 Each time this circuit is opened the relay 71 deenergizes, permitting the spring 173 to again engage the spring 174. The engagement of the said springs 173 and 174 closes an energizing circuit through the slow acting private magnet relay 73 and the vertical magnet 67. This circuit extends from ground G¹¹ through springs 173 and 174, springs 176 and 177, relay 73, vertical magnet 67 and side switch wiper 178 to battery 10 lead 98, thence through battery B to ground G. The vertical magnet is energized four times over this circuit and operates to raise the shaft wipers 64, 65 and 66 to a position opposite the bank level in which are situated the terminals of the desired line #44. 15 The vertical magnet 67 and relay 73 will not energize through the resistance 179 when the relay 71 is energized, this resistance being bridged across the springs 173 and 174 20 to furnish a high resistance path to ground and thus reduce the spark when the contact between these springs is broken. The relay 72, being slow acting, does not have time to deenergize during the time the spring 173 is 25 disengaged from the spring 175 while sending impulses. The relay 73, which is included in the circuit of the vertical magnet, is slow acting also, and is energized by the first impulse, but does not have time to 30 deenergize until all the impulses for the first digit are completed. The relay 73, upon energizing, closes an energizing circuit for the private magnet 69. This circuit extends from ground G¹² through springs 180 and 35 40 45 50 55 60 65 70 75 80 85 90 95 100 105 110 115 120 125 130 135 140 145 150 155 160 165 170 175 180 185 190 195 200 205 210 215 220 the springs 194 and 195 in contact with the springs 196 and 197, respectively. With the key K³ in this position the cord circuit is cut off from the line and the ringer generator L' is bridged across the line of substation #44. A circuit now extends from ground through the ringer generator L', trunk conductor 170, line conductor 10, through the condenser 8 and ringer 7 of substation A, and back over line conductor 11, trunk conductor 171, through springs 195 and 197 to the battery B' and to ground G, whereby the ringer 7 will be operated to notify the subscriber at substation A that his connection has been completed. The engagement of the springs 195 and 197 of the key K³ also furnishes a battery connection for maintaining the holding circuit of the relay 189 of the connector F while the key is operated. After signaling the substation A the key K³ is returned to normal position, and as soon as the called subscriber removes his receiver the substation A is provided with talking battery current from ground G⁹ through the relay 76, over the trunk conductor 170 and line conductor 10, transmitter 6 and receiver 4 of the substation A, back over the line conductor 11 and trunk conductor 171, through the supervisory relay 78 and battery B' to ground G.

When the receiver at the called substation A' is restored to the hook upon the completion of the conversation, the circuit through the supervisory relays 77 and 79 is broken, but the relay 79 is energized over a circuit extending from ground G¹⁵ through the relay 196^a, sleeve conductor of the jack J², thence to the sleeve conductor of the plug P² and through the relay 79 to the battery B. Since the armature 166^a is now attracted by the relay 79 alone it is brought into contact with the contact point 167^a, thereby establishing an energizing circuit from ground G⁹ through the lamp 80. Likewise, when the receiver at the substation A is restored to the switch hook the relay 78 remains energized over a circuit extending from ground G¹⁶ through coil 197, sleeve of jack J' and sleeve of plug P', through relay 78 to the battery B'. The relay 78 attracts the armature 198 against the contact point 199, thereby closing an energizing circuit through the supervisory lamp 81. The simultaneous glowing of the lamps 80 and 81 signifies to the operator that the conversation is completed and she may take down the connection. The release of the switch F is initiated by the removal of the plug P' from the jack J' in the following manner: It will be seen that the holding circuit of the relay 189 is broken when the said plug P' is removed from the jack J'. The relay 189 thereupon deenergizes and permits the springs 190 and 191 to separate, thus opening the holding circuit of the release relay 72. The slow acting relay 72 in turn deenergizes and permits the springs 176 and 200 to engage. Thus an energizing circuit is closed through the release magnet 70, said circuit extending from ground G¹¹ through springs 173 and 174, springs 176 and 200, release magnet 70, normal springs 201 and 202 (which were closed when the shaft was raised the first step) to the battery lead 98, thence through the battery B to ground G. The release magnet energizes and restores the connector F to normal position. When the switch shaft returns to its normal position it separates the springs 201 and 202, thus leaving the release magnet 80 normally deenergized.

Returning now to that part of the operation when the wipers of the connector F had reached the line of substation A, but before the side switch has moved to third position, suppose that the line #44 were busy. In this case the wiper 66 finds a guarding potential present at the private contact 74 or 75, said potential being supplied by some other switch E or F which has made connection with the line, or by the individual switch C of the line if it is a calling line. If the private wiper 66 does find a guarding potential present at the private contact 74 the energizing circuit of the private magnet 69 is maintained after the relay 73 falls back on the cessation of the impulses for the second digit. The energizing circuit for the private magnet now extends from the grounded contact 74 through side switch wiper 184 (bearing in mind that the side switch is still in second position), through springs 203 and 204, relay 205, springs 182 and 181 and private magnet 69 to the battery lead 98, thence through the battery B to ground G. The spring 181 is so adjusted that it engages spring 182 before leaving spring 180, thus preventing the deenergization of the private magnet while its holding circuit is being shifted. The relay 205 is also included in this new circuit through the private magnet 69 and it now energizes. When the relay 205 energizes it shifts spring 204 out of engagement with spring 203 and into engagement with spring 206, whereby the relay 205 and private magnet 69 are disconnected from the grounded contact 74, but at the same time supplied with a holding ground from ground G¹⁷ through the springs 209 and 210 and springs 206 and 204. The side switch is now locked in second position and the busy signaling machine is connected to the trunk conductor 171 through the springs 207 and 208 and side switch wiper 183. The connector F is released from this position also by the removal of the plug P' from the jack J'. In this case the circuit of the slow acting re-

lease relay 72 is opened by the relay 71, which deenergizes when the plug P' is removed.

- Suppose that the subscriber at substation 5 A had desired connection with another subscriber of the branch exchange. In that case the subscriber secures connection with the operator in the same manner as before explained. When the subscriber removes his 10 receiver from the switch hook the line switch trips in to extend the line conductors 10 and 11 to a connector E, and a signal lamp 131 is lighted at the main exchange. The key K' is then thrown to bridge the operator's set 15 across the trunk conductors 124 and 125, and the line switch H operates to connect the conductors 124 and 125 with the same switch E to which the line of the substation A has been extended by the line switch C. Upon 20 learning that a subscriber of the branch exchange is desired the operator simply operates the calling device 87 to cause the switch E to bring the line wipers 43 and 44 into connection with the desired line. It 25 will be remembered that when the line switch H extends the conductors 124 and 125 to the connector E the relays 51 and 52 of the connector E are energized as well as the relay 156 of the line switch H. The relay 51, 30 upon energizing, presses the springs 211, 212 and 213 into engagement, thereby supplying ground to the spring 214 and establishing an energizing circuit for the slow acting release relay 59. This circuit extends from ground 35 G¹⁸ through the springs 211 and 212 and relay 59 to the battery lead 98, thence through battery B to ground G. The relay 52, in its energized position, maintains the circuit of the ringer relay 60 open. When 40 the release relay 59 energizes it shifts the spring 216 out of engagement with the spring 218 and into engagement with the spring 217, thereby disconnecting the spring 219 of the relay 51 from the release magnet 56 and connecting it with the vertical magnet 53. 45

When the calling device is operated for the first digit the circuit of the relays 51 and 52 is opened a certain number of times corresponding to the digit called. The relay 156, (Fig. 2), being slow acting, remains energized while the impulses are being transmitted. Each time the relay 51 deenergizes an energizing circuit is closed through the vertical magnet 53 and slow acting relay 55. This circuit extends from ground G¹⁸ through the springs 211 and 219, 216 and 217, relay 55, side switch wiper 49 and vertical magnet 53 to the battery lead 98, thence through battery B to ground G. The magnet 53 energizes each time the circuit is closed and operates to raise the shaft wipers step by step to a position opposite the bank level containing the terminals of the desired line. As 60 soon as the shaft is raised the first step the

normal springs 57, 57^a and 58 engage, thereby supplying battery current to the release magnet 56, private magnet 50 and ringer relay 60. The slow acting relay 55, which is included in the circuit just traced through the vertical magnet 53, energizes upon the first impulse and remains so until the impulses are completed, when it resumes its normal position. When the relay 55 energizes it closes an energizing circuit through the private magnet 50. This circuit extends from ground G¹⁹ through the springs 220 and 221, private magnet 50, normal springs 57 and 58 to the battery lead 98, thence through battery B to ground G. The private magnet, upon energizing and deenergizing, trips the side switch to second position, whereby the rotary magnet 54 is brought under the control of the relay 51. When the calling device is now operated for the second digit the rotary magnet 54 is actuated to rotate the shaft wipers 43 and 44 onto the terminals of the desired line in the same manner that the vertical magnet 53 was operated to raise the said wipers to the proper bank level. The relay 55 operates the same for the second digit as for the first, and causes the private magnet to release the side switch to the third position. The calling device is now operated once to send at least one impulse to the connector E. This time, when the relay 51 deenergizes, a circuit is established through the relay 222 from ground G¹⁸ through springs 211, 219, 216 and 217, relay 55, side switch wiper 49, contact 223 and relay 222 to battery lead 98, thence through the battery B to ground G. The relay 222, upon energizing, locks itself over a circuit extending from ground G³ through springs 106 and 107, springs 117 and 224 and relay 222 to the battery lead 98, thence through the battery B to ground G. The relay 222, in its energized position, also removes the guarding potential from the auxiliary master switch bank M' and closes a circuit for the release relay 59. This circuit extends from the ground G³ to the spring 117, as formerly traced, thence through spring 225 and relay 59 to the battery lead 98, thence through the battery B to ground G. This circuit is provided for holding the release relay energized in case the operator releases the line switch H before the called subscriber answers, thereby allowing the relay 51 to deenergize and open the circuit of the relay 59 at a point between the springs 211 and 212. The relay 222, in its energized position, also furnishes a guarding potential from ground G³ through springs 106, 107, 117 and 224, bank springs 20 and 19 to the private normal conductor 193^a, and thence to the upper private bank contacts of the calling line.

The relay 222 while energized renders the signal 131 at the operator's position inop-

erative by opening the springs 116 and 117 in the circuit of relay 108, which relay controls said signal so that if the operator should release the key K', the said signal 131 5 will not again be displayed.

Thus it is seen that the guarding potential is not supplied to the calling line until after the side switch has passed to third position. This arrangement is provided so 10 that it will be possible to call back onto the line of the calling subscriber and give him connection with another subscriber on the same line. The called line is provided with a guarding potential by the side switch 15 wiper 48 as soon as it reaches third position.

After the connection has been completed and the operator's key K' is restored the calling subscriber may signal the called subscriber 20 by pressing the push button 2, whereby the resistance 3 is inserted in the circuit of the relays 102 and 103. These relays are so adjusted that when the resistance 3 is included in their circuit the relay 103 remains 25 energized and relay 102 falls back. When the relay 102 falls back an energizing circuit is closed through the ringer relay 60. This circuit extends from ground G³ through springs 106, 107, 105, 104, 214* 30 and 215, relay 60 and normal springs 57* and 58 to the battery lead 98, thence through the battery B to ground G. The ringer relay 60, upon energizing, opens the line connection at a point between springs 226 35 and 227 and connects the ringing generator L to the called line. The circuit of the ringing current extends from ground through the generator L and through springs 228 and 226, side switch wiper 46, shaft wiper 40 43, thence over the line to the called substation and back over shaft wiper 44, side switch wiper 47, ringer relay springs 229 45 and 230 and condenser 61 to ground G²⁰. It will be seen that with this arrangement, when the calling subscriber is ringing back to another substation on his own line, the relay 102 is shunted by the condenser 61 and therefore will not be energized by the ringing current. If so desired the operator 50 may ring the called substation by grounding both sides of the trunk. In this case the relay 51 remains energized while the relay 52 falls back, thus energizing the ringer relay over a circuit extending from ground G¹⁸ 55 through relay springs 211, 213, 214 and 215 and through the ringer relay 60 to the battery lead 98, thence through the battery B to ground G. As soon as the connection is completed the operator's key K' is restored 60 to normal position, whereupon the relay 156 deenergizes to initiate the release of the line switch H and free the trunk 124, 125 in the same manner as previously described. The called substation is supplied with talking 65 battery current from ground G⁸ through re-

lay 52, side switch wiper 47, shaft wiper 44, thence through the substation apparatus and back over shaft wiper 43, side switch wiper 46, ringer relay springs 226 and 227 and relay 51 to the battery lead 98, thence through 70 battery B to ground G.

If the subscriber at substation A hangs up his receiver first upon the termination of the connection, the relays 103 and 102 become deenergized. The separation of the 75 springs of the relay 103 disconnects one ground connection G³ from the cut-off winding 25 of the line switch C, but the relay 222 is still held up by the ground G¹⁸ and maintains a connection between ground G¹⁸ and 80 cut-off winding 25 of the line switch C. Now, when the called subscriber hangs up his receiver the relays 51 and 52 deenergize, thus disconnecting the ground G¹⁸ from the relays 222 and 59 and the cut-off winding 85 25 of the line switch C. When the ground is cut off from the cut-off winding 25 the plunger of the line switch is withdrawn from the bank and the substation A is disconnected from the connector E. The removal of the ground connection from the relay 59 of the connector E allows this relay to deenergize and close an energizing circuit through the release magnet 56. The circuit through the release magnet 56 extends from 90 ground G¹⁸ through relay springs 211, 219, 216 and 218, magnet 56, normal springs 57 and 58 to battery lead 98, thence through the battery B to ground G. The release magnet 56, upon energizing, restores the 100 connector E to normal position. As soon as the switch shaft reaches its normal position it opens the normal springs 57 and 58, thereby cutting battery off of the release magnet 56 and allowing it to deenergize. 105

If the called subscriber restores his receiver to the switch hook first the relays 51 and 52 deenergize, but the relays 222 and 59 are still supplied with ground from ground G³ by the relay 103. In this case the ground 110 is cut off of the relays 222 and 59 when the receiver at the calling substation is hung up and the relay 103 allowed to deenergize. The connector E and line switch C release, in the same manner as before explained, 115 upon the deenergization of the relays 222 and 59.

If the called line is busy when called by the connector E the private magnet does not deenergize when the relay 55 falls back after 120 the last digit is called, but remains energized and locks the side switch in second position and the calling subscriber receives the busy signal in a manner similar to that described for the connector F. The locking circuit 125 for the private magnet 50 of the connector E after the relay 55 falls back extends from the grounded upper private bank contact of the busy line, through shaft wiper 45, side switch wiper 48 (in second position), springs 130

221* and 221 (spring 221 engages spring 221* before it disengages spring 220), private magnet 50 and normal springs 57 and 58 to battery lead 98. The busy signal circuit extends from the secondary winding of the busy signaling machine I through springs 231 and 232, condenser 63, bank springs 18 and 17, line conductor 11, through the substation A, line 10, springs 15 and 16, relay 103, battery lead 98 and thence to the other terminal of the busy signaling machine I. The primary circuit of the busy machine extends from ground G²¹ through the interrupter 233 and primary winding 15 234 to battery lead 98.

It will be seen that it requires a guarding ground upon the upper private bank contact of a busy line to prevent a connector E from obtaining connection with that line, 20 and when connection is extended from a calling line through the connector E this guarding ground for the calling line is not provided until the side switch of the connector has passed to third position. Thus 25 it is possible for the connector E to call back on the calling line to signal some other subscriber thereon in case it is a party line. In case the called subscriber is not on the same line as the calling subscriber the side 30 switch wiper 48, in third position, furnishes a guarding potential through the upper private wiper 45 to the upper private bank contacts of the called line, while the side switch wiper 48*, in third position, furnishes a 35 ground through the lower private wiper 45* to energize the cut-off winding of the called subscriber's line switch C.

In the general arrangement of the system shown in Fig. 4 there are represented two 40 branch exchanges equipped with substations A, line switches C and H and connectors E and F similar to those shown in Figs. 1 and 2. There is also shown a group of main exchange substations A' connected to a manual board N. Two operators' positions of this board N are represented. One position is an ordinary position, where connections between main exchange subscribers are made. The other position is a so-called 50 trunking position—that is, a position where connections are made between different branch exchanges and between branch exchange substations and main exchange substations. The usual order wire between the 55 regular operator's position and the trunking position is represented at R. Besides the apparatus described, there may also be connected with the manual board N a full automatic exchange similar to that disclosed 60 in British Patent No. 26,301 of 1906, and represented herein at T. This automatic exchange comprises substations T', line switches T², first selector switches T³, second selectors T⁴ and connectors T⁵. From 65 some of the bank contacts of the first se-

lectors T³ trunk lines lead to the trunking position of the board N, where they terminate in jacks J⁷ (Fig. 7). Leading from the board N are trunk lines which lead from jacks J⁵ (Fig. 5) to first selectors T³, through 70 the medium of which access may be had to any substation in the automatic exchange. In Fig. 6 there is shown a cord circuit which is suitable for extending connection from any line in the manual exchange to the automatic exchange T. The left-hand end of this cord is the same as the left-hand end of the cord O (Fig. 2), while the right-hand end is provided with a supervisory relay bridged across the talking circuit and with 80 a key K⁶ by means of which a calling device of the proper character for controlling the switches of the automatic exchange T may be connected with the cord. Calls coming in from the automatic exchange may be 85 answered with the cord O (Fig. 2).

From the foregoing it will be seen that I provide an operator's equipment, and means for automatically directing the calls to said equipment, whereby the operator may answer the call and extend the same to the line of the called subscriber. The trunking connection from the manual board to the trunk between the line switch and the connector is not included in the calling connection when one subscriber calls another at the distant exchange, and is released by the operator without disturbing the calling connection. In this way the same trunk and manual equipment can be used for successively answering calls, and for extending each call in the desired direction, the trunk not being an essential part of any calling connection, but being used merely as a means for enabling the operator to control the automatic switches that are provided for connecting calling lines with called lines at the branch or distant exchange. It follows, therefore, that no operator is necessary at the said branch exchange, and that the operator at the main exchange will answer all 100 calls for the distant exchange, and then complete the same to the called lines. When the subscribers at the branch exchange hang up their receivers the automatic connections are 105 released and restored to normal condition.

It will also be seen that I provide an improved connector for use in making reverting calls on party lines, the said connector being provided with a plurality of private 110 wipers and means for grounding each private wiper when the side switch passes to third position. Thus one private wiper is used for closing an energizing circuit through the bridge cut-off relay coil of the 115 called line, and the other private wiper is used for establishing a guarding potential for the party line, or for closing a circuit to automatically prevent the completion of the connection if the called line is busy. 130

I do not limit myself to the exact construction shown and described.

What I claim as my invention is:—

1. In a telephone system, a line, a non-numerical switch for said line, a numerical switch, a trunk leading to said numerical switch adapted to be seized by said non-numerical switch, another trunk, and means for controlling said numerical switch over two sides of both of said trunks in series to extend a talking circuit connection from said line through said switch, which connection excludes one of said trunks. 70
2. In a telephone system, a calling line, a called line, automatic switching means for connecting the two lines together, a manual board, a trunk line leading from said board, an operator's telephone, a manual switch for connecting the telephone with the trunk, an automatic switch for connecting the trunk and calling line, and means for then controlling said automatic switching means over the two sides of said trunk in series and through said automatic switch. 75
3. In a telephone system, a connector provided with line wipers, a pair of auxiliary wipers working simultaneously with the line wipers, means for closing a busy test circuit through one auxiliary wiper, a line, a relay for said line, and means for closing an energizing circuit for said relay through the other auxiliary wiper. 80
4. In a telephone system, a party line, another line, and a connector for enabling one party-line subscriber to call another on the same line, or on the other line, said connector provided with a plurality of wipers, a three-position side switch adapted to ground two of said wipers by movement to the third position, a busy test circuit closed through one of said wipers while the side switch is in second position, a guarding potential connection adapted to be closed by the same wiper when the side switch is in third position, a relay for each line, circuits for said relays controlled by the other of said wipers while the side switch is in third position, a manual board connection by which an operator controls said connector, and means for releasing said manual board connection alone. 85
5. In a telephone system, a line a switch, a trunk line, means for controlling said switch over the two sides of said trunk line in series to extend a talking circuit connection from said line through said switch, which connection excludes the said trunk, and means for releasing said excluded trunk alone. 90
6. In a telephone system, an automatic switch, a trunk line, means for controlling said switch over the two sides of said trunk line in series to extend a talking circuit connection through said switch, which connection excludes said trunk, and means for releasing said excluded trunk alone. 95
7. In a telephone system, a calling line, a called line, automatic switching means for connecting the two lines together, a manual board, a trunk line leading from said board, an operator's telephone, a manual switch for connecting the telephone with the trunk, an automatic switch for connecting the trunk and calling line, means for then controlling said automatic switching means over the two sides of said trunk line in series and through said automatic switch, and means for releasing the trunk alone. 100
8. In a telephone system, a connector provided with line wipers, a pair of auxiliary wipers working simultaneously with the line wipers, means for closing a busy test circuit through one auxiliary wiper, a line, a relay for said line, means for closing an energizing circuit for said relay through the other auxiliary wiper, a manual board connection by which an operator controls said connector, and means for releasing said manual board connection alone. 105
9. In a telephone system, a party line, another line, a connector for enabling one party-line subscriber to call another on the same line, or on the other line, said connector provided with a plurality of wipers, a three-position side switch adapted to ground two of said wipers by movement to the third position, a busy test circuit closed through one of said wipers while the side switch is in second position, a guarding potential connection adapted to be closed by the same wiper when the side switch is in third position, a relay for each line, circuits for said relays controlled by the other of said wipers while the side switch is in third position, a manual board connection by which an operator controls said connector, and means for releasing said manual board connection alone. 110
10. In a telephone system, a line, a non-numerical switch for said line, a numerical switch, a trunk line leading to said numerical switch adapted to be seized by said non-numerical switch, another trunk line, means for controlling said numerical switch over the two sides of said last trunk line in series and a portion of the first trunk to extend a calling connection from said line, which connection excludes one of said trunks, and means for finding said line when called. 115
11. In a telephone system, a calling line, a called line, automatic switching means for connecting the two lines together, a manual board, a trunk line leading from said board, an operator's telephone, a manual switch for connecting the telephone with the trunk, an automatic switch for connecting the trunk and calling line, means for then controlling said automatic switching means over the two sides of said trunk line in series and through said automatic switch, and means for finding the calling line when used as a called line. 120
12. In a telephone system, a connector provided with line wipers, a pair of auxiliary wipers working simultaneously with the line wipers, means for closing a busy test circuit through one auxiliary wiper, a line, a relay for said line, means for closing an energizing circuit for said relay through the other auxiliary wiper, a manual board connection by which an operator controls said connector, and means for releasing said manual board connection alone. 125
13. In a telephone system, a calling line, a called line, automatic switching means for connecting the two lines together, a manual board, a trunk line leading from said board, an operator's telephone, a manual switch for connecting the telephone with the trunk, an automatic switch for connecting the trunk and calling line, means for then controlling said automatic switching means over the two sides of said trunk line in series and through said automatic switch, and means for finding the calling line when used as a called line. 130

- wipers working simultaneously with the line wipers, means for closing a busy test circuit through one auxiliary wiper, a line, a relay for said line, means for closing an energizing circuit for said relay through the other auxiliary wiper, and subscriber-controlled means for releasing said connector by opening the line at the calling substation. 13. In a telephone system, a party line, another line, a connector for enabling one party-line subscriber to call another on the same line, or on the other line, said connector provided with a plurality of wipers, a three-position side switch adapted to ground two of said wipers by movement to the third position, a busy test circuit closed through one of said wipers while the side switch is in second position, a guarding potential connection adapted to be closed by the same wiper when the side switch is in third position, a relay for each line, circuits for said relays controlled by the other of said wipers while the side switch is in third position, and subscriber-controlled means for releasing said connector by opening the line at the calling substation. 14. In a telephone system, a line, a non-numerical switch for said line, a numerical switch, a trunk leading to said numerical switch adapted to be seized by said non-numerical switch, another trunk, and means for controlling said numerical switch over the two sides of said trunks in series to extend a calling connection from said line, which connection excludes one of said trunks. 15. In a telephone system, a calling manual line, a called manual line, automatic switching means, an operator's line, means for setting up a talking connection over the operator's trunk to the calling manual line, and means for controlling said switching means over the two sides of said operator's line in series to connect the calling and called lines together, which calling connection excludes the said operator's line. 16. In a telephone system, a calling line, a called line, automatic switching means for connecting the two lines together, a manual board, a trunk leading from said board, an operator's telephone, a manual switch for connecting the telephone with the trunk, an automatic progressively movable switch for connecting the trunk and calling line to establish a talking circuit with said calling line, and means for then controlling said automatic switching means over the trunk and through said automatic switch, such control being over the two sides of the talking circuit of the trunk in series. 17. In a telephone system, a plurality of trunks, an operator's equipment, means controlled over a calling line for automatically selecting an idle trunk and for extending connection thereto, means for automatically connecting the selected trunk with said equipment to enable the operator to answer the call, and means controlled by the operator over the two sides of said automatic connection in series to extend the call. 18. In a telephone system, an operator's position with answering and calling devices, a calling line, means for automatically connecting the line with said operator's position, and means controlled over the two sides of said automatic connection in series by the operator's calling device to extend the call. 19. In a telephone system, a connector provided with line wipers, a pair of auxiliary wipers working simultaneously with the line wipers, means for closing a busy test circuit through one auxiliary wiper, a line, a relay for said line, means for closing an energizing circuit for said relay through the other auxiliary wiper, a trunk, and means for controlling said connector over the two sides of said trunk in series. 20. In a telephone system, a party line, another line, a connector for enabling one party-line subscriber to call another on the same line, or on the other line, said connector provided with a plurality of wipers, a three-position side switch adapted to ground two of said wipers by movement to the third position, a busy test circuit closed through one of said wipers while the side switch is in second position, a guarding potential connection adapted to be closed by the same wiper when the side switch is in third position, a relay for each line, circuits for said relays controlled by the other of said wipers while the side switch is in third position, a trunk, and means for controlling said connector over the two sides of said trunk in series. 21. In a telephone system, a trunk line having two branches having a common terminal, means for extending a talking connection from said terminal over either of said branches, automatic switches associated with one of said branches, and means for transmitting impulses back over the two sides of the talking circuit of said other branch in series to operate said automatic switches. 22. In a telephone system, a subscriber's line, a trunk line having two branches having a common trunk terminal, a trunk-selecting switch for said subscriber's line for seizing said trunk terminal to extend a talking connection from said line over either branch of said trunk, automatic switches associated with one of said branches, and means for transmitting impulses back over the two sides of the talking circuit of said other branch in series to operate said switches. 23. In a telephone system, a manual switchboard, an automatic switch, a trunk line having two branches having a common

- terminal, one of said branches leading to said switchboard and the other to said automatic switch, means for seizing said common terminal and for extending a talking connection over either of said branches, and means for transmitting impulses back over two sides of the talking circuit of said branch extending to said switchboard in series to operate said automatic switch. 5
24. In a telephone system, a subscriber's line, a manual switchboard, an automatic switch, a trunk line having two branches having a common terminal, one of said branches leading to said switchboard and the other to said automatic switch, a non-numerical trunk-selecting switch for said subscriber's line, means including said switch for seizing said common terminal for extending a talking connection over either 10 of said branches, and means for transmitting impulses back over two sides of the talking circuit of said branch extending to the manual switchboard in series to operate said first-mentioned automatic switch. 15
25. In a telephone system, a manual switchboard, an automatic switch, a trunk line having two branches having a common terminal, one of said branches leading to said switchboard and the other to said automatic switch, means for seizing said common terminal for extending a talking connection over either of said branches, a signal at said switchboard, means for displaying said signal when said trunk is seized, and means for transmitting impulses back over two sides of the talking circuit of said switchboard branch in series to operate said automatic switch. 20
26. In a telephone system, a plurality of subscribers' lines, a trunk line, a manual switchboard, means for extending a connection from one of said subscribers' lines over said trunk to said manual board, means for extending said connection from said board to a second of said subscribers' lines, automatic switches for extending a connection to another of said subscribers' lines, and means at said manual board for transmitting impulses back over said trunk to operate said switches. 25
27. In a telephone system, a main exchange, a branch exchange, a trunk line extending from said branch exchange to said main exchange, said trunk line being adapted for use in completing talking connections extending from a subscriber's line in said branch exchange to a subscriber in said main exchange, automatic switches for completing connections with a called subscriber's line in said branch exchange, and means for transmitting impulses back over two sides of said trunk line in series from said main to said branch exchange to operate said switches. 30
28. In a telephone system, a trunk line having two branches having a common terminal, means for extending a talking connection from said terminal over either of said branches, an automatic switch associated with one of said branches, said switch having contact arms normally disconnected from said trunk, means for transmitting impulses back over the two sides of the other branch of said trunk in series to operate said switch, and means controlled by the operation of said switch for connecting said switch arms with said trunk. 35
29. In a telephone system, a trunk line having two branches having a common terminal, means for extending a talking connection from said terminal over either of said branches, automatic switches associated with one of said branches, a condenser in said trunk, a relay connected with said trunk on one side of said condenser, means for transmitting impulses back over the two sides of said second branch of said trunk in series to operate said relay, and means controlled by the operation of said relay for controlling the operation of said automatic switches. 40
30. In a telephone system, a manual switchboard, an automatic switch, a trunk line having two branches having a common terminal, one of said branches leading to said switchboard and the other to said automatic switch, means for seizing said common terminal for extending a connection over either of said branches, a condenser in one side of said trunk, a relay connected with said trunk on one side of said condenser, means at the manual switchboard for transmitting impulses back over two sides of one branch of said trunk in series to operate said relay, and means controlled by the operation of said relay to control the operation of said automatic switch. 45
31. In a telephone system, a manual switchboard, an automatic switch, a trunk line having two branches having a common terminal, one of said branches leading to said switchboard and the other to said automatic switch, means for seizing said common terminal, a relay connected with said trunk, an impulse transmitter at said manual switchboard for transmitting impulses over two sides of said trunk in series to intermittently energize said relay, and means controlled by said intermittent energizations of said relay to transmit a series of grounded impulses to said automatic switch to control the operation thereof. 50
32. In a telephone system, a subscriber's line, a plurality of trunk lines, a trunk-selecting switch adapted to make connection with an idle one of said trunks, each of said trunks having two branches, a spring jack at the end of one of said branches, an automatic switch in which the other branch terminates, and means associated with said 55

spring jack for transmitting impulses back over two sides of one branch in series to operate the automatic switch associated with the other branch of said trunk.

5. 33. In a telephone system, a line, a second line, a signal associated with said second line, an automatic progressively movable switch for establishing connection between said first and second lines responsive to a single impulse of current and for thereby operating said signal, a third line, an automatic progressively movable switch for said third line, means for operating said switch in response to said signal for extending connection from said third line to said second line in response to a single impulse of current.

34. In a telephone system, a group of lines, an automatic switch for each one of said lines, a second group of lines, signaling means associated with said second group of lines, means for operating any one of said switches for establishing a connection between its line and any one of said second lines in response to a single impulse of current, and for thereby giving a signal to an operator through the instrumentality of said signaling means, another line, an automatic switch for said other line, means for operating said last automatic switch in response to said signal, said switch operable to select said established connection and to connect said other line with said established connection as a result of a single impulse.

35. 35. In a telephone system, a plurality of lines, a pair of test circuits for each line, connector switches having access to said lines, means for applying a guarding potential to either of said circuits separately, one of said connectors responsive when the potential is applied to either test circuit, and another responsive when the potential is applied to only one of said circuits.

36. In a telephone system, a line, a pair of test circuits for said line, connector switches having access to said line, means for applying a busy potential to one of said circuits to prevent one of said connectors from establishing a connection with said line and for applying a potential to the other circuit to prevent all of said connectors from establishing a connection with said line.

37. In a telephone system, a calling manual line, a called manual line, automatic switching means, an operator's line, an automatic progressively movable switch for connecting said calling line and said operator's line, and means for controlling said switching means over the two sides of said operator's line in series to connect the calling and called lines together, said last connection excluding said operator's line.

38. In a telephone system, a calling telephone line, a trunk line terminating in an automatic connector switch, an individual

line switch responsive to the removal of the receiver on the calling line for extending connection to said trunk line, a finder switch and a branch of said trunk line accessible thereto, an operator's position and a call signal thereat actuated upon the seizure of said trunk line, means whereby the operator may initiate the operation of said finder switch to establish connection with said branch, and means whereby the operator may then control said connector over a circuit extending through said finder switch and over a conductor of said branch to complete the connection to a called line.

39. In a telephone system, a calling telephone line, a trunk line terminating in an automatic connector switch, an individual line switch responsive to the removal of the receiver on the calling line for extending connection to said trunk line, a finder switch and a branch of said trunk line accessible thereto, an operator's position and a call signal thereat actuated upon the seizure of said trunk line, means whereby the operator may initiate the operation of said finder switch to establish connection with said branch, means whereby the operator may then control said connector over a circuit extending through said finder switch and over a conductor of said branch to complete the connection to a called line, and means for releasing said finder switch without interfering with the connection.

40. In a telephone system, subscribers' lines, trunk lines, individual line switches for said subscribers' lines for connecting with idle trunk lines, a finder switch having access to said trunk lines for extending one to which connection has been established to an operator's position, and a master switch for controlling said line switches and said finder switch.

41. In a telephone system, means for setting up a talking circuit between a calling and a called subscriber's line, a connector switch for seizing the called line controlled over two sides of the talking circuit in series, means controlled by the calling subscriber for releasing said switch, and means for preventing a calling subscriber from releasing said switch.

42. In a telephone system, a calling and a called line, means including a trunk line and a connector switch for connecting the subscribers on said lines in conversation, said connector being controllable over the two sides of said trunk line in series, and means for releasing said connector controlled by whichever one of said subscribers who last replaces his receiver.

43. In a telephone system, a manual switchboard, an automatic switch, a trunk line having two branches having a common terminal, said branches normally connected to said terminal, one of said branches lead-

- ing to said switchboard and the other to said automatic switch, means for seizing said common terminal, a condenser in said trunk, a relay bridged across said trunk on one side of said condenser, a signal at said switchboard controlled by said relay, and means for transmitting impulses back over said trunk from said manual switchboard to operate said automatic switch.
- 10 44. In a telephone system, a manual switchboard, an automatic switch, a trunk line having two branches having a common terminal, said branches normally connected to said terminal, one of said branches leading to said switchboard and the other to said automatic switch, means for seizing said common terminal, a condenser in said trunk, a relay bridged across said trunk on one side of said condenser, a signal at said switchboard controlled by said relay, a second relay connected with said trunk on the other side of said condenser, means at said manual switchboard for intermittently energizing said second relay, and means controlled by the operation of said second relay for controlling the operation of said automatic switch.
- 15 45. In a telephone system, a manual switchboard, an automatic switch, a trunk line having two branches having a common terminal, said branches normally connected to said terminal, one of said branches leading to said switchboard and the other to said automatic switch, means for seizing said common terminal for extending a connection over either of said branches, a condenser in one side of said trunk, a relay connected with said trunk on one side of said condenser, means at the manual switchboard for transmitting impulses back over one branch of said trunk to operate said relay, means controlled by the operation of said relay to control the operation of said automatic switch, whereby a talking circuit is set up over the said common terminal through the medium of said manual switchboard, and lines divided into groups extending from said automatic switch, said switch having motion in one plane to select groups and motion in a plane at right angles thereto to find a line in a selected group.
- 20 46. In a telephone system, a manual switchboard, an automatic switch, a trunk line having two branches having a common terminal, said branches normally connected to said terminal, one of said branches leading to said switchboard and the other to said automatic switch, means for seizing said common terminal, a condenser in said trunk, a relay bridged across said trunk on one side of said condenser, a signal at said switchboard controlled by said relay, means for transmitting impulses back over said trunk from said manual switchboard to operate said automatic switch, and lines divided into
- 25 groups extending from said automatic switch, said switch having motion in one plane to select groups and motion in a plane at right angles thereto to find a line in a selected group.
- 30 47. In a telephone system, a manual switchboard, an automatic switch, a trunk line having two branches having a common terminal, said branches normally connected to said terminal, one of said branches leading to said switchboard and the other to said automatic switch, means for seizing said common terminal, a condenser in said trunk, a relay bridged across said trunk on one side of said condenser, a signal at said switchboard controlled by said relay, a second relay connected with said trunk on the other side of said condenser, means at said manual switchboard for intermittently energizing said second relay, means controlled by the operation of said second relay for controlling the operation of said automatic switch, and lines divided into groups extending from said automatic switch, said switch having motion in one plane to select groups and motion in a plane at right angles thereto to find a line in a selected group.
- 35 48. In a telephone system, a manual switchboard, an automatic switch, a trunk line having two branches having a common terminal, one of said branches leading to said switchboard and the other to said automatic switch, means for seizing said common terminal, a condenser in said trunk, a relay bridged across said trunk on one side of said condenser, a signal at said switchboard controlled by said relay, means for transmitting impulses back over said trunk from said manual switchboard to operate said automatic switch, said signal associated with one of the branches, and means under the control of said automatic switch for rendering said signal inoperative over the trunk.
- 40 49. In a telephone system, a manual switchboard, an automatic switch, a trunk line having two branches having a common terminal, one of said branches leading to said switchboard and the other to said automatic switch, means for seizing said common terminal, a condenser in said trunk, a relay bridged across said trunk on one side of said condenser, a signal at said switchboard controlled by said relay, a second relay connected with said trunk on the other side of said condenser, means at said manual switchboard for intermittently energizing said second relay, means controlled by the operation of said second relay for controlling the operation of said automatic switch, said signal associated with one of the branches, and means under the control of said automatic switch for rendering said signal inoperative over the trunk.
- 45 50. In a telephone system, a plurality of subscribers' lines, a trunk line having two

- branches and a common terminal, a manual switchboard, means for extending a connection from one of said subscribers' lines over one branch of said trunk to said manual switchboard, means for extending said connection from said board to a second of said subscribers' lines, an automatic switch in the other branch for extending said connection from said first subscriber's line to another of 5 said subscribers' lines over the common terminal, means at said manual board for transmitting impulses back over said trunk to operate said switch, lines divided into groups extending from said automatic switch, said switch having motion in one plane to select groups and motion in a plane at right angles thereto to find a line in a selected group, a signal associated with one of the branches, and means under the control of the automatic switch in the other branch for rendering said signal inoperative 10 over the trunk.
51. In a telephone system, a manual switchboard, an automatic switch, a trunk line having two branches having a common terminal, one of said branches leading to said switchboard and the other to said automatic switch, means for seizing said common terminal for extending a connection over either of said branches, a condenser in one side of said trunk, a relay connected with said trunk on one side of said condenser, means at the manual switchboard for transmitting impulses back over one branch of said trunk to operate said relay, means controlled by the operation of said relay to control the operation of said automatic switch, whereby a talking circuit is set up over the said common terminal through the medium of said means at said manual switchboard, lines divided into groups extending from said automatic switch, said switch having motion in one plane to select groups and motion in a plane at right angles thereto to find a line in a selected group, a signal associated with one of the branches, and means under the control of said automatic switch in the other branch for rendering said signal inoperative over the trunk.
52. In a telephone system, a manual switchboard, an automatic switch, a trunk line having two branches having a common terminal, one of said branches leading to said switchboard and the other to said automatic switch, means for seizing said common terminal, a condenser in said trunk, a relay bridged across said trunk on one side of said condenser, a signal at said switchboard controlled by said relay, means for transmitting impulses back over said trunk from said manual switchboard to operate said automatic switch, lines divided into groups extending from said automatic switch, said switch having motion in one plane to select groups and motion in a plane at right angles thereto to find a line in a selected group, a signal associated with one of the branches, and means under the control of said automatic switch in the other branch for rendering said signal inoperative over the trunk.
53. In a telephone system, a manual switchboard, an automatic switch, a trunk line having two branches having a common terminal, one of said branches leading to said switchboard and the other to said automatic switch, means for seizing said common terminal, a condenser in said trunk, a relay bridged across said trunk on one side of said condenser, a signal at said switchboard controlled by said relay, a second relay connected with said trunk on the other side of said condenser, means at said manual switchboard for intermittently energizing said second relay, means controlled by the operation of said second relay for controlling the operation of said automatic switch, lines divided into groups extending from said automatic switch, said switch having motion in one plane to select groups and motion in a plane at right angles thereto to find a line in a selected group, a signal associated with one of the branches, and means under the control of said automatic switch in the other branch for rendering said signal inoperative over the trunk.

Signed by me at Chicago, Cook county, Illinois, this 13th day of June, 1910.

FRITZ LUBBERGER.

ARTHUR J. RAY,

DISCLAIMER.

1,306,824.—*Fritz Lubberger, Chicago, Ill. SEMI-AUTOMATIC TELEPHONE-EX-
CHANGE SYSTEM.* Patent dated June 17, 1919. Disclaimer filed July 15,
1920, by the assignee, *Automatic Electric Company*.

Enters this disclaimer—

"To claims 41 and 42 in the said specification, which are in the following words, to wit:

"41. In a telephone system, means for setting up a talking circuit between a calling and a called subscriber's line, a connector switch for seizing the called line controlled over two sides of the talking circuit in series, means controlled by the calling subscriber for releasing said switch, and means for preventing a calling subscriber from releasing said switch.

"42. In a telephone system, a calling and a called line, means including a trunk line and a connector switch for connecting the subscribers on said lines in conversation, said connector being controllable over the two sides of said trunk line in series, and means for releasing said connector controlled by whichever one of said subscribers who last replaces his receiver." [Official Gazette August 3, 1920.]
